US00D990160S

(12) **United States Design Patent** (10) Patent No.: **US D990,160 S**
Wang (45) Date of Patent: **** Jun. 27, 2023**

(54) **LUGGAGE**

(71) Applicant: **GUANGZHOU LUGGEX TECHNOLOGY CO. LTD.**
 Guangzhou (CN)

(72) Inventor: **Kaihong Wang**, Guangzhou (CN)

(**) Term: **15 Years**

(21) Appl. No.: **29/884,224**

(22) Filed: **Feb. 8, 2023**

(51) LOC (14) Cl. **03-01**

(52) U.S. Cl.

USPC **D3/279**

(58) **Field of Classification Search**

USPC D3/201, 273, 276, 279, 281, 289

CPC A45C 5/00; A45C 5/03; A45C 2005/032;

A45C 2005/037; A45C 5/14; A45C 2005/142

See application file for complete search history.
